LINT REMOVER

Erwin Howard Wilbrecht, Shadow Mountain Fairway
Cottages, No. 4A, Palm Desert, Calif.

Filed June 3, 1963, Ser. No. 75,163

Term of patent 14 years

(Cl. D9—2)

FIG.—2

FIG.—1

FIG. 1 is a perspective view of a lint remover, showing my new design;

FIG. 2 is a top plan view thereof;

FIG. 3 is a front elevation thereof; and

FIG. 4 is an elevation of the left side thereof.

The undisclosed right side of the lint remover is substantially the same in appearance as the left side shown in FIG. 4. The undisclosed rear of the lint remover is substantially the same in appearance as the front shown in FIG. 3.

I claim:

The ornamental design for a lint remover, as shown and described.
